E. R. BURTNELL

INTERNAL COMBUSTION ENGINE

Filed Nov. 22, 1923

Inventor: -
Everett R. Burtinett,
By Martin P. Smith, Atty.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed November 22, 1923. Serial No. 676,279.

My invention relates to internal combustion engines of the general type disclosed in my co-pending application for U. S. Letters Patent filed January 4, 1923, Serial No. 5 610,700.

The principal object of my present invention is to generally improve upon and simplify the construction of the invention disclosed in my application aforesaid and 10 to provide an engine of the two-stroke cycle type that will produce a relatively high degree of efficiency with relatively low cost of operation.

Further objects of my invention are to 15 provide an engine of the character described wherein a pair of combustion chambers are connected at their upper or outer ends by a common clearance space which performs the functions of a common combustion and 20 expansion chamber; to arrange behind and in line with the combustion chambers a gaseous fuel pumping cylinder, the axis of which is substantially parallel and in the same plane with the axes of the combustion 25 cylinders; to arrange on one side of the pumping cylinder and laterally with respect to the plane occupied by the axes of the combustion and pumping cylinders, a cylinder and a piston valve therein which 30 piston valve controls the admission of gaseous fuel into the pumping cylinder; and to actuate such piston valve from a secondary or auxiliary crank shaft that is driven at the same speed as the main crank shaft of 35 the engine and to which latter the pistons in the combustion cylinders and pumping cylinders are connected.

With the foregoing and other objects in view, my invention consists in the novel 40 features of construction and arrangement of parts that will be hereinafter more fully described and claimed, and illustrated in the accompanying drawings, in which—

Figure 1 is a vertical section lengthwise 45 through the center of an engine of my improved construction;

Figure 2 is a vertical section taken on the line 2—2 of Figure 1;

Figure 3 is a horizontal section taken approximately on the line 3—3 of Figure 1;

Figure 4 is a detail sectional view showing the transfer duct from the pumping

cylinder to the adjacent combustion cylinder.

Referring by numerals to the accompanying drawings, which illustrate a practical embodiment of my invention, 10 designates a cylinder block which is preferably cast in a single piece and the walls of which are provided with connected chambers 11, through which may be circulated a fluid cooling medium such as water, for the purpose of disseminating the heat generated during operation of the engine.

Formed in the cylinder block 10, is a pair of combustion chambers, 12 and 13 and a pumping chamber 14, said chambers being arranged in a row with their axes substantially parallel and occupying the same plane.

Formed in said block 10, to one side of the pumping chamber 14, is a piston valve chamber 15, the axis of which is substantially parallel with the axis of said pumping chamber. Secured to the top of block 10 is a head 16, provided with a chamber 17, through which may be circulated fluid cooling medium, and formed in the underside of this head and connecting the upper portions of the combustion chambers 12 and 13, is a common clearance chamber 18.

Formed in the underside of head block 16, is a shallow chamber 19, that is disposed substantially at right angles to the chamber 18, and said chamber 19 establishes communication between pumping chamber 14 and piston valve chamber 15.

Leading from the end of chamber 19, that communicates with chamber 14, is an outlet 20 that communicates with a duct 21, the lower end of which communicates with an inlet port 22 that is formed in the block 10 at a point intermediate the ends of combustion chamber 13.

Seated in the central portion of block 16 and preferably above the combustion chamber 13, is an ignition device, such as a spark plug 23 and the terminals of the electrodes thereof project into the chamber 18.

Formed through the wall of block 10 in the same horizontal plane with port 22, is an exhaust port 24 that leads from the intermediate portion of combustion chamber 12.

Arranged beneath the block 10 is a suit-

ably formed crank case 25, having bearings 26 in its ends for a crank shaft 27, and the latter being provided with two cranks 28 and 29. These cranks are oppositely disposed or arranged approximately 180 degrees apart, and crank 28, which is approximately twice the length of crank 29, but with the same radius of throw, is located beneath chambers 12 and 13, while crank 29 is located beneath chamber 14.

Arranged for reciprocatory movement within chambers 12 and 13 are pistons 30 and 31 respectively and these pistons are connected by ordinary connecting rods 32 to crank 28.

A pumping piston 32 is arranged for operation within chamber 14 and a connecting rod 33 connects said piston with crank 29.

Arranged for rotation in suitable bearings 20 in the crank case 25, is a secondary crank shaft 34, the axis of which is parallel with the axis of crank shaft 27, and this secondary crank shaft is directly connected to the said crank shaft 27, so as to rotate it 25 at the same speed by meshing pinions 35, as shown, or by sprocket wheels and a chain.

The crank shaft 34 is arranged beneath the piston valve cylinder 15 and arranged for operation. Within the latter is a piston 30 valve 36, the same being connected to the crank of shaft 34 by a connecting rod 37.

Formed through the wall of the cylinder block that surrounds chain 15, is a gaseous fuel inlet port 38, the latter being arranged 35 so that it is wholly open when piston valve 36 is at the lower end of its stroke.

The operation of my improved engine is as follows:

While piston valve 36 is at the lower end 40 of its stroke, a charge of gaseous fuel enters chamber 15 through open port 38 and this charge of gaseous fuel also fills chamber 19 and the pumping chamber 14. At the time the piston valve 36 is at the lower end of 45 its stroke, pumping piston 32 is approximately at the half way point on its downward stroke, and as the piston valve 36 moves upward, inlet port 38 is closed, and on the succeeding upward stroke of pumping 50 piston 32, the gaseous fuel charge drawn into the chambers 14 and 15 will be compressed therein and also in the connecting chamber 19 and in the duct 21.

Pistons 30 and 31 move downward together following ignition of a compressed 55 gaseous fuel charge in the common chamber 18 and the upper portions of chambers 12 and 13, and as said pistons approach and pass low center, or the lower ends of their 60 travel, inlet port 22 and exhaust port 24 will open, so that the compressed gaseous fuel charge will pass from duct 21, through port 22, into and through chamber 13, thereby driving before it, the products of combustion 65 from the previously ignited charge, and said

products of combustion, or the greater portion thereof, will be forced out through exhaust port 24 as long as the same is open.

As piston 30 starts on its upward or inward movement, ports 24 and 22 are closed, 70 and as the pistons 30 and 31 continue their upward travel, the charge of gaseous fuel admitted to the connected combustion chambers and the residual products of combustion remaining therein will be compressed in chamber 18 and the upper portions of chambers 12 and 13 and at the point of highest compression, or as the power pistons 30 and 31 pass their high centers, the compressed charge will be fired by a spark produced between the terminals of the electrodes or spark plug 23.

As the compressed charge is thus ignited, the relatively high pressure following combustion will drive the pistons 30 and 31 80 downward on their power stroke.

Thus it will be seen that I have provided a relatively simple two stroke cycle internal combustion engine, having twin power cylinders, a gaseous fuel pumping cylinder, said three cylinders being arranged in a row and a gaseous fuel inlet controlled piston valve that is arranged laterally of the pumping pistons and which piston valve is operated from crank shaft that is driven directly from the main crank shaft of the engine, and which arrangement provides a very compact structure that may be economically operated in point of fuel consumption.

It is obvious that construction of the engine, as herein shown and described, may be modified in minor details without departing from the spirit of my invention, the scope of which is set forth in the appended 100 claim.

I claim as my invention:

A two stroke cycle internal combustion engine unit of four cylinders, two of the cylinders being joined by a single compression and combustion clearance chamber 110 that is formed lengthwise parallel with the axes of the crank shaft, exhaust ports in one of the two cylinders that are joined by the single clearance chamber, inlet ports formed in the wall of the outer one of the two cylinders that are joined by the single clearance chamber, a charge pumping cylinder, a piston valve cylinder, inlet ports formed in the wall of said piston valve cylinder, a single compression clearance chamber joining said pump cylinder and the piston valve cylinder, the piston valve cylinder being disposed to the side of and parallel with the pumping cylinder, the compression clearance chamber that joins the pump cylinder and the piston valve cylinder extending laterally with respect to the plane occupied by the row of three cylinders, a separate crank shaft 115 for driving the piston valve, engine speed actuated driving means between the main 120

crank shaft and said separate crank shaft, a duct extending from one end of the lateral clearance chamber, that joins the piston valve cylinder to said pump cylinder, to an 5 inlet port formed in one of the combustion cylinders arranged in the row of three cylinders, a separate connection between

each of the pistons in the combustion cylinders and the charge volume pumping cylinder and the main crank shaft and said main 10 crank shaft having a separate bearing periphery for each connection.

In testimony whereof I affix my signature.
EVERETT R. BURTNETT.
